SLIDE COMPASS

Warren D. Novak, 325 Douglas Road,
Chappaqua, N.Y. 10514

Continuation of design application Ser. No. 13,338,
Aug. 30, 1968. This application May 29, 1969, Ser.
No. 17,540

Term of patent 14 years

Int. Cl. D10—08

U.S. Cl. D52—6

FIG. 1 is a front elevational view of a slide compass embodying my new design;

FIG. 2 is a side elevational view thereof;

FIG. 3 is a side elevational view taken from the opposite side as FIG. 2;

FIG. 4 is a rear elevational view thereof;

FIG. 5 is a top plan view thereof; and

FIG. 6 is a bottom plan view thereof.

This is a continuation of Design application Ser. No. D. 13,338, filed Aug. 30, 1968 and now abandoned.

I claim:

The ornamental design for a slide compass, substantially as shown and described.
